DESIGN FOR A FEEDER BOX FOR GRAIN OR THE LIKE

Waldo E. Foster, Minneapolis, Minn., assignor to
Conveyors Incorporated, St. Paul, Minn., a cor-
poration of Minnesota

Application January 29, 1945, Serial No. 117,644

Term of patent 14 years

(Cl. D55—1)

To all whom it may concern:

Be it known that I, Waldo E. Foster, a citizen of the United States, residing at Minneapolis, in the county of Hennepin and State of Minnesota, have invented a new, original, and ornamental Design for a Feeder Box for Grain or the like, of which the following is a specification, reference being had to the accompanying drawing, forming part thereof:

Figure 1 is a front elevational view of a Feeder

Box for Grain or the like, showing my new design;
Figure 2 is a top plan view of the same; and
Figure 3 is a side elevational view of the same.
The side and end of the feeder box for grain
or the like not shown in the drawing are sub-
stantially like the side and end shown.

I claim:

The ornamental design for a feeder box for
grain or the like, as shown and described.

WALDO E. FOSTER.
